[57] **CLAIM**

The ornamental design for a combined football helmet bottle twist-off opener and key chain, as shown and described.

DESCRIPTION

FIG. 1 is a top left side perspective view of a combined football helmet bottle twist-off opener and key chain showing our new design;

FIG. 2 is a left side view thereof, the undisclosed right side view being a mirror image thereof;

FIG. 3 is a front view thereof;

FIG. 4 is a bottom view thereof;

FIG. 5 is a top view thereof; and,

FIG. 6 is a back view thereof.

The key chain is omitted in FIGS. 1-6 for ease of illustration.
